FLUID COMPRESSOR COOLING SYSTEM

James I. Bevan, East McKeesport, Pa.

Application August 16, 1946, Serial No. 691,082

3 Claims. (Cl. 230—211)

1

This application is a continuation-in-part of my co-pending application, Serial No. 656,291, filed March 22, 1946.

This invention relates to a fluid compressor cooling system, and more particularly to such a device adapted for the cooling of any fluids, in combination with a compressor.

A primary object of this invention is the provision of an improved device characterized by means whereby in conjunction with a compression cylinder a fluid to be cooled is sucked into the device and expelled partially through a cooling unit and partially into a storage tank in such manner that the automatic cooling of portions of the fluid is effectively accomplished.

As conducive to a clearer understanding of this invention, it may here be pointed out that it is typical of air compressors that the air which is drawn from the atmosphere becomes heated when compressed. If not dissipated, this heat will overheat the machine and literally burn it.

An important object of this invention, therefore, is the provision of means whereby an air compressor will operate at a materially reduced temperature.

An additional object of the invention is the provision of such a device wherein the fluid passed through the cooling system is subsequently circulated about the fluid applied directly to the storage tank, and admixed therewith in such manner that the fluid ultimately expelled to the storage tank is substantially cooler than that originally admitted to the device.

A further object of the invention is the provision of such a device that will be sturdy and durable in construction, reliable and efficient in operation, and relatively simple and inexpensive to manufacture, assemble and install.

Other objects will in part be obvious and in part be pointed out as the description of the invention proceeds, in conjunction with the accompanying drawings, wherein there are disclosed some preferred embodiments of this inventive concept.

In the drawings:

Figure 1 is a transverse sectional view, partially schematic, of one form of device embodying features of the instant inventive concept, as applied to a single cylinder.

Figure 2 is a similar view showing a modified form of construction.

Figure 3 is a side elevational view of a multiple cylinder compressor.

Having reference now to the drawings, and more particularly to Figure 1, there is generally

indicated at 10 a cylinder having positioned therein a reciprocating piston 11 adapted to be moved in any desired manner to provide alternative suction and compression strokes. The upper portion of the cylinder 10 is provided with an inlet 12 which leads into a chamber 13 closed by a partition 14 and having at its lower extremity a check valve 15 of any desired conventional type adapted upon the suction stroke to open 10 to permit access of the fluid into the main body of the cylinder 10 and to close on the compression stroke.

On the other side of the partition 14 is a radial chamber 16 provided with an outlet 17 leading to suitable storage tanks (not shown) and surrounding coaxially a smaller inner chamber 18. The chamber 18 is provided with a check valve 19 of any desired conventional type adapted to be opened upon the compression stroke of the piston 11 and closed on the suction stroke thereof. An outlet 20 leads from the chamber 18 to a cooling unit in the form of a coil 21 of any desired conventional configuration, the opposite extremity of which enters through an inlet 22 a chamber 23 provided at its lower extremity with a check valve 24 of any desired type correspondingly adapted to open on the compression stroke of the piston 11 and close on the suction stroke. The chamber 23 is in communication through a port 25 with the chamber 16 surrounding the chamber 18.

Thus, it will be seen that in the operation of the device, when the piston 11 moves downwardly on the suction stroke, the valve 15 is opened and fluid is admitted from the inlet 12 into the main body of the cylinder 10. Conversely, on the opposite stroke the valves 19 and 24 are both opened, and a certain proportion of the fluid is forced through the valve 19 into the chamber 18 and through the cooling unit 21 back inwardly into the chamber 23. Correspondingly, an additional proportion of the fluid is passed directly through the valve 24 into the chamber 23 and thence through the port 25 into the chamber 16 and outwardly through the outlet 17 directly to the storage tank.

The dilution of the hot air passing through valve 24 by the relatively cool air originating through the inlet 22 and the valve 15 results in considerably lower operating temperatures than obtainable with other types of air-cooling systems.

Having reference now to the modification disclosed in Figure 2, there is generally disclosed at 30 a cylinder similar to the cooling cylinder 10

and correspondingly provided with a piston similar to the piston 11 (not shown).

Fluid is admitted to the cylinder 30 through a port 31 which leads into an annular or peripheral chamber 32 surrounding a valve mechanism including a threaded header block 33 having radial ports 34 leading into an aperture 35 below the block 33. A lower closure plate 36 is provided with annular ports 37 adapted to be closed by means of a valve member 38 spring-biased by a spring 39 and a plate 40, the latter being secured to the plate 36 by a bolt 41 and nut 42. It will thus be seen that upon the suction stroke of the piston the valve member 38 is opened downwardly against the bias of the spring 39, permitting the passage of the fluid admitted through the port 31, through the chamber 32, and through the ports 34 and the ports 37 into the main bore of the cylinder 30. On the opposite side of the cylinder there is provided an aperture 41 closed by a plate 42 having a centrally positioned valve aperture 43, or series of apertures, closed by a valve 44 spring-biased by a spring 45, held in position by a nut 46 and bolt 47 to a header closure plate 48. The plate 48 is provided with apertures 49 permitting the passage of fluid admitted upwardly through the ports 43 into a chamber 50 which communicates through an outlet 51 with a cooling unit 52. The opposite end of the cooling unit 52 enters through an aperture 53 into a chamber 54 coaxial with the chamber 50, through which the admission of fluid from the cylinder 30 is permitted, by means of ports 55 disposed concentrically with the ports 43 and closed by valve members 56 spring-biased by a coil spring 57 secured in position between the valve members 56 and the header plate 48. An outlet pipe 58 leads to an outlet pipe 59, which, in turn, leads to a storage tank or an additional stage, as may be desired.

In its essentials, the operation of this modification of the device is substantially identical to that previously disclosed, the sole distinction being in the arrangement of parts. In this modification, upon the suction stroke, the valve member 38 is opened downwardly, and upon the compression stroke, the valves 56 and 44 are correspondingly opened upwardly, a certain portion of the fluid being admitted to the chamber 54, and an additional portion to the chamber 50. Said fluid entering the chamber 50 passes through the cooling unit 52 and is readmitted to the chamber 54, whereupon the admixed fluid passes through the port 58 into the outlet 59 in the manner previously discussed.

In Figure 3, I have illustrated the invention as applied to a multi-cylinder machine comprising a bank of cylinders 60, 61 and 62, each cylinder having a reciprocating piston therein. As the structure of the cylinders is the same, only one of such cylinders will be specifically described. The cylinder 60 comprises a first chamber 80 arranged above the piston 81 and adjacent one side thereof, and a second chamber 68' likewise arranged above the piston 81 and adjacent the opposite side of the cylinder. The chamber 80 is provided with a port 65 which is connected to a source of fluid supply, the port being for the admission of a fluid from said source into the chamber 80. A valve 63 of the structure as heretofore described in connection with the valve mechanism for the chamber 32 is in the chamber 80, the valve 63 controlling the discharge of the fluid from the chamber 80 into the cylinder 60. The chamber 68' has a valve 64 for con-

trolling the admission therein of fluid from the cylinder 60, and a port 82 to which an end of a cooling coil 76 is connected thereto.

The valve 64 is provided with a closure plate 66 held in position by the lower end of a sleeve 67 threaded in the top of a third chamber 68 surrounding the sleeve 67, the lower portion of the sleeve being spaced from the walls of the chamber and having openings 69 therein to provide open communication between the chamber 68 and the interior space of the sleeve 67 constituting the second chamber 68'. The closure plate 66 is formed with ports 70 closed by an annular valve member 71 positioned on top of the plate and held in closed downward position by a coil spring 72 which surrounds a valve guide 73 above the plate 66. A washer 74 secured at the top of the valve guide forms an abutment for the upper end of the spring.

20 A cooling coil or unit 75 connects the top of the second chamber of cylinder 61 to the side of the chamber 68 of cylinder 60, and a cooling coil or unit 76 connects the top of the chamber 68 of the cylinder 60 to the top of the second chamber of cylinder 62, so that the compressed fluid from cylinder 61 passes through the chamber 68' of cylinder 60 and combines with compressed fluid from cylinder 60 to pass through the second chamber of cylinder 62 to combine with the compressed fluid therefrom. An outlet pipe 77 leads from the second chamber of cylinder 62 to a storage tank or to the next stage of a compound machine.

From the foregoing it will now be seen that there is herein provided an improved fluid compressor cooling system which accomplishes all the objects of this invention, and others, including many advantages of great practical utility and commercial importance.

40 As various embodiments may be made of this inventive concept, and as various modifications may be made in the embodiment hereinbefore shown and described, it is to be understood that all matter herein is to be interpreted merely as illustrative and not in a limiting sense.

45 I claim:

1. A fluid compressor cooling system, the combination of a bank of compression cylinders arranged in side-by-side relation, a reciprocating piston in each of said cylinders, each cylinder comprising a first chamber arranged above said piston and adjacent one side of the cylinder, there being a port in said chamber and connected to a source of fluid supply for admitting fluid from said source into said chamber, a valve in said chamber for controlling the discharge of the fluid from said chamber into said cylinder, a second chamber in said cylinder arranged above said piston adjacent the opposite side of said cylinder, a valve for said second chamber for controlling the admission therein of fluid from said cylinder, said second chamber being provided with an opening, a cooling conduit operatively connected to the opening in the second chamber of one cylinder in the bank and to the port of the second chamber of the adjacent cylinder in the bank for conveying the fluid discharged therein from the second chamber of the adjacent cylinder into the second chamber of said one cylinder, and a second cooling conduit connecting the port of the second chamber of said one cylinder to the port of the second chamber of the cylinder in the bank adjacent to said adjacent cylinder for conveying the fluid discharged

therein from the second chamber of said one cylinder into the second chamber of the cylinder adjacent to said adjacent cylinder.

2. In a fluid compressor cooling system, the combination of a bank of compression cylinders arranged in side-by-side relation, a reciprocating piston in each of said cylinders, each cylinder comprising a first chamber arranged above said piston and adjacent one side of the cylinder, there being a port in said chamber and connected to a source of fluid supply for admitting fluid from said source into said chamber, a valve in said chamber for controlling the discharge of the fluid from said chamber into said cylinder, a second chamber in said cylinder arranged above said piston adjacent the opposite side of said cylinder, a valve for said second chamber for controlling the admission therein of fluid from said cylinder, there being a port in said second chamber, said second chamber being provided with an opening, a third chamber surrounding said second chamber, there being an inlet port in said third chamber, a cooling conduit connecting the inlet port of the third chamber of one cylinder in the bank to the port of the second chamber of the adjacent cylinder in the bank for conveying the fluid discharged therein from the second chamber of the adjacent cylinder into the third chamber in said one cylinder, and a second cooling conduit connecting the port of the second chamber of said one cylinder to the port of the second chamber of the cylinder in the bank adjacent to said adjacent cylinder for conveying the fluid discharged therein from the second chamber of said one cylinder into the second chamber of the cylinder adjacent to said adjacent cylinder.

3. In a fluid compressor cooling system, the combination of a bank of compression cylinders arranged in side-by-side relation, a reciprocating piston in each of said cylinders, each cylinder comprising a first chamber arranged above said piston and adjacent one side of the cylinder, there

being a port in said cylinder and connected to a source of fluid supply for admitting fluid from said source into said chamber, a valve in said chamber for controlling the discharge of the fluid from said chamber into said cylinder, a second chamber in said cylinder arranged above said piston adjacent the opposite side of said cylinder, a valve for said second chamber for controlling the admission therein of fluid from said cylinder, there being a port in said second chamber, said second chamber being provided with an opening, a cooling conduit operatively connected to the opening in the second chamber of one cylinder in the bank and to the port of the second chamber of the adjacent cylinder in the bank for conveying the fluid discharged therein from the second chamber of the adjacent cylinder into the second chamber of said one cylinder, a second cooling conduit connecting the port of the second chamber of said one cylinder to the port of the second chamber of the cylinder in the bank adjacent to said adjacent cylinder for conveying the fluid discharged therein from the second chamber of said one cylinder into the second chamber of the cylinder adjacent the said adjacent cylinder, and conduit means operatively connected to the second chamber of the cylinder adjacent the said adjacent cylinder for conveying the fluid from the latter chamber to said source of supply.
